His Attorney

UNITED STATES PATENT OFFICE.

ALBERT H. SIMMONS, OF OAK PARK, ILLINOIS, ASSIGNOR TO EDISON ELECTRIC APPLIANCE COMPANY, INCORPORATED, OF CHICAGO, ILLINOIS, A CORPORATION OF NEW YORK.

ELECTRIC HEATER.

Application filed July 11, 1924. Serial No. 725,497.

My invention relates to electric heaters, more specifically to electric table grills, and has for its object the provision of a simple, reliable and economical device of this character.

In carrying out my invention I construct the heater of a comparatively few parts which are simple and rugged in construction and which may be manufactured at low cost and easily assembled. I also provide a knock-down feature whereby the device may be conveniently separated into sections which may be nested together into a comparatively small space.

For a more complete understanding of my invention reference should be had to the accompanying drawing in which Fig. 1 is a plan view partially in section showing an electric heater embodying my invention; Fig. 2 is a side elevation of the heater shown in Fig. 1; Fig. 3 is a fragmentary sectional view along the line 3—3 of Fig. 1 looking in the direction of the arrows; Fig. 4 is a fragmentary detail view showing the latching means for the detachable parts of the heater; while Fig. 5 is a fragmentary sectional view along the line 5—5 of Fig. 2 looking in the direction of the arrows.

Referring to the drawing, in carrying out my invention in one form I provide a metallic supporting grid 10 having openings 10^a on which the article to be heated is placed. This grid may be any convenient shape and is shown as rectangular. Around the sides of the grid is a supporting flange 11 which is integral with the grid. The construction of the grid and supporting flange is such that oppositely disposed grooves or recesses 12 and 13 are formed at the junction or bend between the grid and the flange, these grooves opening downward on the lower side of the grid. As shown, the upper supporting surface of the grid is struck downward somewhat in forming the grooves 12 and 13 whereby a ridge is formed around the edge of the grid corresponding to the recesses 12 and 13 on the lower side. The grid and flange may be stamped from a sheet of metal.

The peripheral recesses may, in fact, form a continuous recess around the edge of the grid although, as shown, the two oppositely

disposed recesses 12 and 13 only may be utilized in supporting insulators 14 and 14^a which in turn support a helical heating resistor wire 15. For convenience in manufacture the insulators 14 and 14^a are made in sections, the insulator 14 being shown as comprising short end sections 16 and 17 and a longer central section 18, while the insulator 14^a comprises two long sections 19 and 19^a which are similar in construction to the section 18. The insulators are provided with longitudinal ridges 20 which seat in the grooves 12 and 13, and they are secured in the grooves by means of brackets 21 secured by suitable bolts or rivets to the flange 11.

Spaced along the lengths of the insulators 14 and 14^a are downwardly extending hook-shaped projections 22, and the construction and arrangement of the sections 16 to 19 inclusive is such that these projections, with the exception of the outer projections on the short sections 16 and 17, are in staggered relation from side to side of the grid. The resistance conductor 15 is looped around the projections 22 and passed from side to side of the grid in substantially parallel lengths. The lengths of the resistance conductor are supported centrally by means of a transverse bar 15^a of insulating material provided with apertures through which the resistance conductor passes and secured at its ends to the sides of the grid. As shown, the short insulator sections 16 and 17 are each provided with two projections 22, while the longer sections 18, 19 and 19^a are each provided with three projections. The two projections on the short sections are spaced closely together whereby the outer projections of the short sections are opposite the outer projections of the long sections and form a support for the ends of the resistance conductor. The ends of the resistance conductor are bent around the outer projections of the short sections toward each other and are connected to terminal pins 23 and 24 secured to flange 11 in insulated relation thereto centrally of one side of the grid. These terminal pins project outward and form a convenient means for connecting the resistance conductor 15 to a suitable electrical source of supply. The electrical connection may be established by means of

an attachment plug of any suitable well known form. A guard 25 is provided around the terminal pins.

5 A handle 30 is attached to one side of the grid, preferably to the side opposite the terminal pins 23 and 24. This handle is secured by means of a bolt 31 extending centrally of the handle and entering a nut 32 which is seated in a plate 33 secured to 10 the flange 11, the plate 33 being struck outward to provide a space in which the nut is seated and secured against rotation.

15 The grid with the heating unit, handle and various other parts previously described forms a unitary structure, the body of the heater. This body member is detachably secured to a supporting member comprising a reflector plate 35 to which legs 36 are secured. Preferably, the edge of the 20 reflector plate is struck downward slightly and forms a support on which the body member rests, the central portion of the reflector plate fitting into the body member, as shown in Fig. 5. The body and supporting member are secured together on one side by means of ears 37 struck upward and outward from the metal of the reflector. These ears form locking projections and extend through apertures 38 in one side of the body. 25 On the side opposite the projections 37 the body and supporting member are secured together by means of a latching arm 39 secured to the reflector plate and having a projection 40 which extends upward 30 through an aperture 41 in the reflector plate and through an aperture 42 in the side of the body. A protuberance 43 is provided on the reflector plate for holding the arm 39 in latching position. By retracting the arm 40 it will be observed that the projection 40 can be withdrawn from aperture 42 so that the body member can be tilted upward and released from the supporting member. The body and supporting member may then be 45 nested together into the smallest possible space for shipment.

50 While I have described my invention as embodied in concrete form and as operating in a specific manner in accordance with the provisions of the patent statutes, it should be understood that I do not limit my invention thereto, since various modifications thereof will suggest themselves to those skilled in the art without departing from the spirit of my invention, the scope of which is set forth in the annexed claims.

55 What I claim as new and desire to secure by Letters Patent of the United States is:—

60 1. An electric heater comprising a grid provided with oppositely disposed elongated recesses, insulators removably secured to said grid in said recesses, projections on said insulators, and a resistance conductor supported by said projections.

65 2. An electric heater comprising a grid

provided with elongated recesses at opposite sides in its lower surface, insulators secured to said grid in said recesses, and a resistance conductor supported by said insulators.

3. An electric heater comprising a grid 70 provided with longitudinally disposed recesses at opposite sides, insulators having portions fitting in said recesses, means for holding said insulators in said recesses whereby said insulators are secured to said 75 grid, and a resistance conductor supported by said insulators.

4. An electric heater comprising a grid provided with elongated recesses at opposite sides on its lower surface, insulators clamped 80 in said recesses so as to be secured to said grid projections on said insulators, and a resistance conductor looped around said projections extending from side to side of said grid.

85 5. An electric heater comprising a grid provided with recesses at opposite sides, insulators provided with upwardly extending ridges fitting in said recesses and downwardly extending hook shaped projections, 90 means for securing said insulators in said recesses, and a resistance conductor supported by said projections and passing from side to side of said grid.

95 6. An electric heater comprising a metal grid formed with ridges at opposite sides on its upper surface and with grooves in its lower surface corresponding with said ridges, insulators fitting in said grooves provided with projections, means for clamping 100 said insulators in said grooves whereby said insulators are secured, and a sinuous resistance conductor supported by said projections.

105 7. An electric heater comprising a metal grid formed with grooves at opposite sides in its lower surface, a plurality of separate insulators fitting in each of said grooves, said insulators being provided with projections, means for clamping said insulators in 110 said grooves whereby said insulators are secured, and a sinuous resistance conductor supported by said projections.

115 8. An electric heater comprising a grid having its sides bent downward to provide a support and so as to form oppositely disposed recesses at the bends, insulators clamped in said recesses provided with hook shaped projections, and a resistance conductor looped around said projections and 120 passing from side to side of said grid.

125 9. An electric heater comprising a grid having its sides bent downward to provide a support and so as to form oppositely disposed recesses at the bends, insulators provided with upwardly extending ridges fitting in said recesses and downwardly extending hook shaped projections, means secured to the sides of said grid for securing said insulators, and a resistance conductor 130

looped around said projections and passing from side to side of said grid.

10. An electric heater comprising a body member including a grid having its sides bent downward to provide a support for the grid and so as to form oppositely disposed grooves underneath the grid at the junction of the sides, insulators fitting in said grooves provided with downwardly projecting hooks, clamping members on said sides for

securing said insulators in said grooves, a resistance conductor looped around said hooks and passing from side to side of said grid, a supporting member including a reflector plate, legs secured to said plate, and means for detachably securing said body member to said supporting member. 15

In witness whereof, I have hereunto set my hand this 2nd day of July, 1924.

ALBERT H. SIMMONS.
